Letter Patent

The Subscribers referred to in their Letter Patent once making part of the sum containing a description of the same in the words of the said Antonie & Peter & Henry Hoover heretofore of their improvement in the method of distilling Spirituous Liquors.

It is known that Mr. Antonie Hoover and Henry Hoover, of Waynesboro in the County of Franklin and State of Pennsylvania have made a new and useful improvement in the method of distilling Spirituous Liquors which is described as follows, referring back to the annexed drawings of the same, making part of this Specification.

This improvement is designed principally to save expense in fuel and labor. It is effected by using steam to heat the stillings stills and water contained in the several back stills and bittles which were formerly heated by separate fire. In the present mode one fire being used to heat the water in the main boiler which generates the steam required for the above purposes. A valve in the tube for generating the steam. B. The furnace. C. The stillings still. D. Doubting still containing the coarse heat. E. The coarse heat to the globe tube. F. The globe. G. The pitcher & the water heater & the boiler to the doubting still which may be heated by fire as well as steam. H. Steam pipe leading the steam to pipe to heat the water. I. Pipe to heat the doubting & pipe to heat the boiler from the water heater. & charging pipe to charge the stilling still from the globe tube. K. A pipe from the pump around the boiler and connecting still. L. Intake pipe from the furnace to the stilling still.

The stilling and doubting still may be partly heated by the fire by means of the fire and smoke piping tubes and annex them in the tubes before mentioned. What we claim as our invention and which we desire to secure by Letter Patent consists in the above described method of distilling Spirituous Liquors.
